UNITED STATES PATENT OFFICE.

JOSEPH M. SALADINER, OF BRYAN, TEXAS.

AERIAL TORPEDO.

1,152,226.

Specification of Letters Patent. Patented Aug. 31, 1915.

Application filed April 17, 1915. Serial No. 22,071.

To all whom it may concern:

Be it known that I, JOSEPH M. SALADINER, citizen of the United States of America, residing at Bryan, in the county of Brazos 5 and State of Texas, have invented certain new and useful Improvements in Aerial Torpedoes, of which the following is a specification.

This invention relates to aerial torpedoes, 10 and has particular reference to a device for carrying bombs through the air, and automatically dropping the same at predetermined points, without the aid of the hand of man, or aid of cannon, upon or in proximity to objects to be damaged or destroyed. 15

The invention is designed primarily for use in warfare, and its object is to carry explosives or bombs over an enemy's position and automatically drop the same thereon for 20 destructive purposes.

The invention consists in the construction, arrangement and combination of the several parts of the device as will be hereinafter described, illustrated in the drawings, and 25 more particularly pointed out in the claims hereto appended.

In the drawings Figure 1 shows my aerial torpedo, loaded with bombs, in side elevation; Fig. 2 is a top plan view of the carriage, the superimposed gas holder removed, 30 showing the relative arrangement of the several parts thereof; Fig. 3 is an enlarged vertical cross-sectional view of one of the bomb holding tubes, taken on line 3—3 of Fig. 4, 35 showing a bomb held in position therein, and means for automatically releasing the same; Fig. 4 is a horizontal sectional view taken on line 4—4, Fig. 3, showing a bomb, bomb holding, and bomb releasing mechanism; Fig. 5 is a vertical longitudinal sectional view, broken away, of the bomb holding tube, showing the neck of a bomb in position, mechanism for holding the same therein, and mechanism for automatically 40 releasing said bomb, and Fig. 6 is a vertical cross-sectional view of one of the bomb holding tubes showing the horizontal stepped partition therein, and the manner of hinging and locking the two tube sections together. 45

Referring to the drawings by numerals, 1 indicates a generally cigar-shaped gas holder made of any suitable material, preferably rubber, and has extending longitudinally therethrough a rod or shaft 2, the ends

thereof projecting through the ends of said 55 gas-holder, as shown in Fig. 1, the ends of said gas holder being so secured to said shaft 2 as to be air-tight. Surrounding the gas-holder 1 is a suitable netting 3, adapted to limit the distension of the holder, under 60 pressure, beyond a predetermined extent, and to maintain its shape. This netting is secured at its forward end in a fixed clamp 4, rigidly secured to said shaft 2 just in front of the forward end of the gas holder, 65 and the rear end thereof in a suitable clamp 5 slidably mounted on the rear projecting end of said shaft 2, and may be loosened or tightened by means of the screw at the end of said shaft, as is evident. 70

The numeral 7 indicates a suitable carriage located beneath the gas-holder, and secured to the ends of the shaft 2 by means of the hangers 8 and 9, as shown in Fig. 1. Located in this carriage in any desired position, is a box or compartment 10 in which the motive power for running the device is located, and 11 indicates the driving shaft having at the outer end thereof the propeller 12. Secured on the shaft 11, between the 80 propeller and the box 10, is a suitable worm 13, for a purpose hereinafter stated.

Secured to the sides of the carriage 7 are suitable tubes 14, 14, the front ends thereof being secured to the forward ends of said 85 carriage, and their rear ends in lugs or brackets 15, 15, at the rear end of said carriage, as shown. Each of these tubes 14 is made up of two semi-cylindrical sections 16 and 17, which are hinged together so that 90 access to the interior thereof, may be easily and quickly had, and when closed, are securely locked together by means of the latches 18, as is evident. The forward ends of these tubes 14, 14, are slotted, and provided on each side of each slot with upstanding ears 19, 19, in which are mounted the reels 20, 20, as shown. 95

21, 21, indicate means, preferably leaf-springs, bearing on said reels, for retarding 100 the rotation thereof when in use. The lower semi-cylindrical portion 17 of these tubes 14, 14, is provided with a stepped horizontal partition 22, providing at one side a chain race 23, and the other side a series of pockets 105 24, having the forward side thereof downwardly and rearwardly inclined, as shown at 25, and the bottom and outside of said pocket

cut away as shown, for a purpose hereinafter stated.

26, 26 indicate suitable brackets secured to the rear end of the carriage 7, and in which is journaled a shaft 27, having at each end thereof, sprocket-wheels 28, mounted on the outside of said brackets 26, 26, and adjacent to and in alinement with the open ends of the tubes 14, 14, for a purpose hereinafter described. Secured to the underside of said carriage in alinement with said sprocket-wheels 28, 28, are idler pulleys 29, 29, also for a purpose to be herein-after set forth. Secured rigidly upon the shaft 27, immediately above and in mesh with the worm 13 on the shaft 11, is a worm gear 30 adapted to operate the sprocket-wheels 28 when said shaft 11 is operated, as is evident. The brackets 26, 26 are so secured to the rear of the carriage 7, either by sliding connections, or hinges, that they, and the shaft 27 carried thereby, may be raised in order to disengage the worm gear 30 from the worm 13, on the shaft 11, so that the sprocket-wheels 28, 28, and the chains 31, 31 operated thereby, will not commence to operate until the machine is about to fly, and said worm gear 30, is caused to engage said worm 13.

30 The numerals 31, 31, indicate suitable sprocket chains adapted to slide in the chainraces 23, 23, in the tubes 14, 14, the forward ends thereof being secured in the reels 20, 20, and wound thereon, and the rear ends thereof adapted to pass out of the rear ends of said tubes 14, 14, and over the sprocket wheels 28, 28, and down over the idler pulleys 29, 29. Secured on each chain at a predetermined point is a finger 32. Pivoted on the upper step of the partition 22 to the rear of each pocket 24 is a trigger 33 having rollers in each end thereof, one end of said trigger being adapted to project into the pocket 24 toward the inclined side thereof, and the opposite end to project over the chain race 23 and slightly above the chain therein, said trigger being adapted to be operated by the finger 32 on said chain, for a purpose hereinafter set forth. The chains 31, 31, in addition to providing means for automatically dropping the bombs are also a distance gager, that is, they are provided with a scale indicating miles and fractions thereof, whereby 55 the length of chain to be wound upon the reels to permit the torpedo to travel a given distance before the dropping of bombs is to be commenced, is ascertained by the register of such indicated point upon the chain with 60 the rear end of the tube 14.

The numerals 34, 34, indicate bombs, which I call the mother bombs, because they carry a plurality of smaller bombs, provided with goose-neck ends 35 adapted to 65 be carried by my aerial torpedo. The ends

35 of the bombs are set through the sides of the tubes 14, 14, into the pockets 24, 24, and rest against the downwardly inclined sides thereof and upon the adjacent ends of the triggers 33, and are releasably held therein by means of said triggers 33, as shown in Figs. 3 and 4. The triggers 33 are held in position, against accidental displacement, by the weight of the bombs resting on the ends thereof, and will not be 75 shifted until operated by the trips or fingers 32 carried by the chains 31, as is apparent.

34' indicates a guard hinged to the side of the tubes and is for the purpose of preventing the bombs being accidentally removed or displaced from the positions in the said pockets.

The operation of the device is as follows: The distance of the points, at which the bombs are to be dropped, from the starting point having been ascertained, the chains are wound upon the reels 20, 20, until the fingers 32 carried thereby are in a predetermined position. The bombs are then placed in proper position in the pockets 24 and are releasably held therein by the triggers 33, and the guards 34' set to prevent displacement thereof. The device is then aimed at the object to be attacked, and the motive power started, when the device, loaded with its bombs, will rise and fly toward its destination. As the propeller shaft 11 revolves it will, of course, operate the shaft 27, geared therewith, by means of the worm 13 and gear 30, and the sprocket-gears 28, 28, carried thereby. As the gears 28 rotate, they will withdraw the sprocket-chains 31, 31, from the reels 20, 20, through the chain-race 23, at such rate that, by the time the torpedo has reached the point where it is desired to commence dropping the bombs, the finger 32 on the chains 31, will contact with and operate the triggers 33, 33, of the bombs to be dropped first, and releasing said bombs and permitting them to slide from the pockets 24 and fall to the ground, or upon the object to be attacked, and exploded. Each successive bomb is caused to drop in the same manner as the device continues its flight, until all the bombs have been disposed of, as is apparent. The sprocket chain as it is withdrawn from the reels by the sprocket gears, passes down over the idler pulleys and is thereby prevented from contacting with the propeller, as is evident.

It is understood that I do not confine myself to the precise structure herein shown, as it is evident that changes and modifications may be made therein, without departing from the spirit of my invention.

The said air torpedo has one great secret of far more importance than those given above that should only be given out to the Commander in Chief of the Army. This is known as a blind surprise.

Having thus described my invention, what I claim is:

1. An aerial torpedo having in combination therewith a bomb-carrier arranged longitudinally thereof, a plurality of bomb-holding receptacles in said carrier each having a downwardly inclined side, means for releasably holding bombs in position against said inclined sides, and means for automatically releasing said bombs from said receptacles at predetermined intervals.

2. An aerial torpedo having in combination therewith a longitudinally arranged bomb-carrying device having a series of bomb-holding receptacles therein, said receptacles being provided with bomb supporting mechanisms, adapted in conjunction with the sides of said receptacles to releasably hold a bomb in position therein, and means carried by said bomb-carrying device adapted to engage and actuate said bomb supporting mechanism to automatically release the bomb and permit the same to drop from said bomb-carrying device.

3. An aerial torpedo having in combination therewith longitudinally arranged bomb-carrying devices having a series of bomb-holding receptacles therein, each of said receptacles having its forward side downwardly and rearwardly inclined and open at its bottom, said receptacles being provided with bomb supporting mechanisms adapted, in conjunction with said inclined sides, to releasably support and hold a bomb in position therein, and means carried by said bomb-carrying devices adapted to engage and positively actuate said bomb supporting mechanisms to automatically release the bombs and permit the same to drop from the devices.

4. An aerial torpedo having in combination therewith a propelling mechanism, a longitudinally arranged bomb-carrying device having a series of bomb-holding receptacles therein, each of said receptacles having its forward side rearwardly and downwardly inclined and open at its bottom and provided with a bomb-holding and supporting mechanism, adapted, in conjunction with said inclined side, to releasably hold a bomb in position therein, and means carried by said bomb-carrying device and operated from said propelling mechanism, adapted to engage and positively actuate said bomb-supporting mechanisms to automatically release the bombs and permit the same to drop from the device.

5. An aerial torpedo having in combination therewith a carriage, a longitudinally arranged bomb-carrying device located at each side of said carriage and secured thereto to the outside thereof, a series of bomb-holding receptacles in said bomb-carrying devices, each of said receptacles having its forward side downwardly and rearwardly

inclined and open at its bottom, and provided with a bomb-holding and supporting trigger adapted, in conjunction with said inclined side, to releasably hold and support a bomb in position in said receptacle, and a longitudinally operating trigger-actuating mechanism carried by said bomb-carrying devices adapted to engage said bomb-holding and supporting triggers to positively actuate the same to automatically release the bombs and permit the same to drop from the devices.

6. An aerial torpedo having in combination therewith a carriage and torpedo propelling mechanism carried thereby, a longitudinally arranged bomb-carrier located at each side of said carriage and secured thereto to the outside thereof, a series of bomb-holding receptacles arranged in said carriers, each of said receptacles having its forward side rearwardly and downwardly inclined and its bottom and outer side open, longitudinally operating releasing devices carried by said bomb-carriers, bomb-holding and supporting triggers mounted adjacent to each receptacle and having one end projecting into said receptacle and its opposite end lying in the path of said longitudinally operating releasing devices, whereby said triggers are engaged and positively actuated to automatically release the bombs and permit the same to drop from the carriers.

7. An aerial torpedo having in combination therewith a longitudinally arranged bomb-carrying device having a series of bomb-holding receptacles therein having their bottoms and one of their outer sides open, each of said receptacles being provided with a bomb-supporting and holding mechanism adapted, in conjunction with a side thereof, to releasably hold a bomb in position therein, and means carried by said bomb-carrying device adapted to engage and positively actuate said bomb supporting and holding mechanisms to automatically release the bombs and permit the same to drop from said bomb-carrying device, and a reel located at the forward end of said bomb-carrying device upon which said trigger engaging means is adapted to be wound prior to the starting of the torpedo.

8. An aerial torpedo having in combination therewith a longitudinally arranged bomb-carrying device having a series of bomb-holding receptacles therein with open bottoms, each of said receptacles being provided with bomb-supporting and holding mechanism, a reel at the forward end of said bomb-carrying device, and a longitudinally operating mechanism adapted to be wound upon said reel before the starting of the torpedo, said longitudinally operating mechanism being adapted to be unwound from said reel to engage and positively ac-

tuate the bomb-holding and supporting mechanism to release the bomb and permit the same to drop from the device, and means for unwinding said mechanism from said reel.

9. An aerial torpedo having in combination therewith a longitudinally arranged bomb-carrier having a series of bomb-holding receptacles therein with open bottoms, 10 pivotally mounted bomb-holding and supporting triggers adapted to releasably hold a bomb in each of said receptacles, a reel at the forward end of said bomb-carrier,

and means adapted to be wound upon said reel, and when unwound therefrom during 15 the flight of the torpedo, to engage said bomb-holding and supporting triggers and positively actuate the same to automatically release the bombs from said receptacles.

In testimony whereof I have affixed my 20 signature in presence of two witnesses.

JOSEPH M. SALADINER.
